UNITED STATES PATENT OFFICE.

JOSEPH GERMIN, OF CHICAGO, ILLINOIS.

DESIGN FOR AN ELECTRIC TABLE DECORATION.

41,010.

Specification for Design.

Patented Nov. 29, 1910.

Application filed September 24, 1910. Serial No. 583,690. Term of patent 14 years.

To all whom it may concern:

Be it known that I, JOSEPH GERMIN, a subject of the Emperor of Austria-Hungary, residing at Chicago, in the county of Cook and State of Illinois, have invented a new, original, and ornamental Design for an Electric Table Decoration, of which the following is a specification, reference being had to the accompanying drawing, forming part thereof.

The figure is a side view of an electric table decoration, showing my new design.

I claim:

The ornamental design for an electric table decoration, as shown.

JOSEPH GERMIN.
